(57) **CLAIM**

The ornamental design for an electrical connector housing, as shown and described.

DESCRIPTION

FIG. 1 is a front perspective view of an electrical connector housing showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof, the left side elevational view being a mirror image of FIG. 7;

FIG. 8 is a cross-sectional view taken along line 8—8 in FIG. 3; and,

FIG. 9 is a cross-sectional view taken along line 9—9 in FIG. 3.
